UNITED STATES PATENT OFFICE.

LOUIS C. HILLER, OF MERIDEN, CONNECTICUT, ASSIGNOR TO THE MERIDEN SILVER PLATE COMPANY, OF SAME PLACE.

DESIGN FOR A METAL BORDER.

SPECIFICATION forming part of Design No. 22,460, dated May 23, 1893.

Application filed April 15, 1893. Serial No. 470,541. Term of patent 3½ years.

To all whom it may concern:

Be it known that I, LOUIS C. HILLER, a citizen of the United States, residing at Meriden, in the county of New Haven and State of Connecticut, have invented and produced a new and original Design for a Metal Border; and I do declare the following to be a full, clear, and exact description of the same, reference being had to the accompanying drawing, forming a part thereof.

The figure is a representation of my novel design in plan.

The leading feature of the design consists in a representation of a sheet of ice broken at the edges the same constituting the center

and being encircled by conventional rococo ornamentation.

1 denotes the center of the border representing a sheet of ice which is broken at the edges as at 2, and 3 denotes conventional ornamental waves of so-called rococo style.

What I claim is—

The design for metal border substantially as herein shown and described.

In testimony whereof I affix my signature in presence of two witnesses.

LOUIS C. HILLER.
